UNITED STATES PATENT OFFICE

98,299

DESIGN FOR A COMBINED SALT AND PEPPER SHAKER

Harry J. Edison, Kasson, Minn.

Application December 5, 1935, Serial No. 59,909

Term of patent 7 years

To all whom it may concern:

Be it known that I, Harry J. Edison, a citizen of the United States, residing at Kasson, Dodge County, Minnesota, have invented a new, original, and ornamental Design for a Combined Salt and Pepper Shaker, of which the following is a specification, reference being had to the accompanying drawing, forming a part thereof, wherein

Fig. 1 is a view in side elevation of a combined salt and pepper shaker, showing my new design;

Fig. 2 is a top plan view of the same;

Fig. 3 is a view in side elevation of the same;

and

Fig. 4 is a bottom plan view of the same.

I claim:

The ornamental design for a combined salt and pepper shaker, substantially as shown.

HARRY J. EDISON.
